JESSE E. KRESKY, OF PETALUMA, CALIFORNIA.

LIQUID-FUEL BURNER.

Application filed April 11, 1927. Serial No. 182,632.

My invention relates to burners adapted to use liquid fuel such as kerosene and distillate and in which the liquid fuel is converted into a gas to be burned.

5 Burners in which kerosene or a comparable fuel is formed into a gas to be burned are well known and usually comprise a chamber in which the liquid fuel is heated and gasified. They also usually include a plurality 10 of fuel outlet or release apertures thru which the gas escapes in a number of jets to be burned as it issues therefrom. In such burners it is often difficult to secure an equal distribution of gas to all of the fuel release 15 apertures so that a steady, evenly distributed flame results. Poor distribution sometimes is caused by cross drafts of air which displace the jet of fuel issuing from the nozzle. Usually there are adjusting means provided for regulating the quantity of fuel issuing from the nozzle and the resultant amount of flame. The adjusting means are subject to leakage and liquid fuel flows over the surface of the burner and is apt to ignite, giving rise to serious consequences. The distribution of gases is adversely affected by the expansion and contraction of the metal in which the fuel release apertures are situated. This is particularly the case with burners in which the apertures are made by sawing slots or cuts in a hollow member which conducts the gaseous fuel. Expansion and working of the metal tends to bind and close the slots and reduces unevenly the quantity of fuel issuing therefrom.

It is therefore an object of my invention to provide a burner in which the combustible gas is burned in a plurality of jets to which the gas is evenly distributed.

Another object of my invention is to provide means for conducting any fuel which leaks from the burner to a safe place.

Another object of my invention is to provide a plurality of apertures thru which fuel is released and which are not appreciably affected by expansion or contraction of the surrounding metal.

An additional object of my invention is to provide a fuel nozzle which is freely supplied with air but which is protected from cross drafts.

My invention possesses other advantageous features, some of which with the foregoing, will be set forth at length in the following description where I shall outline in

full that form of the liquid fuel burner of my invention, which I have selected for illustration in the drawings accompanying and forming part of the present specification. In said drawings I have shown one form of 60 liquid fuel burner embodying my invention, but it is to be understood that I do not limit myself to such form since the invention, as set forth in the claims, may be embodied in a plurality of forms. 65

In the drawings:

Fig. 1 shows the burner of my invention in longitudinal section, the plane of section being indicated by the line 1—1 of Fig. 5, and portions of the device being shown in elevation. 70

Fig. 2 is a plan of the burner of my invention.

Fig. 3 is a plan of the starting wick for the burner. 75

Fig. 4 is a front elevation of the burner.

Fig. 5 is a transverse section of the burner, the plane of section being indicated by line 5—5 of Fig. 1.

Fig. 6 shows in perspective one of the 80 burner bars included in the closure for the mixing chamber.

Fig. 7 is a cross section of the fuel nozzle of the burner, the plane of section being indicated by the line 7—7 of Fig. 4. 85

The liquid fuel burner of my invention preferably comprises a mixing chamber having a sump disposed below an associated fuel nozzle and arranged to protect the nozzle from cross drafts, together with a closure 90 for the mixing chamber which includes a plurality of irregular burner bars adapted to form, in connection with interposed spacer strips, a plurality of fuel release apertures in communication with the mixing chamber 95 thru channels adapted to give an even distribution of the fuel.

In the preferred embodiment of my invention disclosed in the drawings, a mixing chamber 6 is provided in which the liquid fuel which preferably has previously been vaporized is mixed with air in combustible proportions. The mixing chamber is usually of cast metal and is formed with supporting legs 7 for positioning the burner on a suitable base. The chamber 6 includes a bottom wall 8, side walls 9 and end walls 10 which are preferably made integrally. The remaining side of the mixing chamber 6 is sealed by a closure 11 which includes a plate 110

- 12 having a pair of similar flanges 13 thereon forming a gas tight union with the upper ends of the sides 9 and the ends 10. The plate 12 is apertured longitudinally, as at 14, 5 to provide an outlet from the mixing chamber 6. Intermediate the ends of the base plate 12 a bridge 16 is provided to strengthen the base plate and to aid in distributing the gases flowing from the mixing chamber. 10 Overlying the aperture 14 is a conduit such as a channel iron 17 in communication with the mixing chamber iron 6 thru the aperture 14. The channel iron 17 is preferably secured to the mixing chamber 6 by bolts 18. 15 At each end of the channel iron 17, a notched support 19 is affixed to support a vaporizing tube 21. The vaporizing tube is provided at one end with a connection 22 thru which liquid fuel, such as kerosene or distillate, is supplied to the burner. To aid in the distribution of the fuel over the interior of the tube 21, a fuel distributor 23 is provided which preferably is a metal rod having a number of circumferential flanges thereon. 20 25 The distributor 23 is preferably inserted thru the end to which the connection 22 is attached. The distributor is spaced from the other end of the tube 21 by a wire 24 which abuts an upstanding tube 26 intersecting the vaporizing tube 21 at substantially a right angle. The tube 26 extends downwardly to associate with one end of the mixing chamber 6. The tube 26 is laterally positioned by a segmental, notched plate 27 adjustably secured to the base plate 12 by a screw 28. At its lower end, the tube 26 is squared and is sealed by means of a cap screw 29. A nozzle 31 fits into a transverse bore in the tube. The nozzle includes a spray tip 32 screwed into the squared portion of the tube 26 and having an aperture 33 of a predetermined size. Also screwed into the squared lower portion of the tube 26 is a body 34 carrying an adjustable needle valve 36 packed by a gland 37. 30 35 40 45 50 55 60 65 70 75 80 85 90 95 100 105 110 115 120 125 130
- Manual adjustment of the needle valve 36 regulates the amount of fuel which can discharge thru the aperture 33 and thereby regulates the rate of combustion of the burner. The spray tip 32 is situated in axial alignment with a horizontal sleeve 38 located in an aperture in the end wall 10 and also supported by a transverse wall 39 passing across the mixing chamber 6. A bail 41 secured to one end of the sleeve 38 affords convenient means for sliding the sleeve in and out of the end wall to vary the amount of air which mixes with the fuel issuing from the tip 32 and thereby affords means for varying to any desired extent the proportion of fuel and air. 60 Occasionally, liquid fuel issues from the nozzle 31 in excessive quantities and drips from the nozzle. In order to trap such liquid fuel and conduct it away from the burner, preferably back to the fuel tank, the forward end of chamber 6 is preferably formed

into a sump 42 provided with a drain pipe 43 leading to any suitable point of disposal of the collected fluid.

Fuel issuing from the burner tip 32 and mixing with air regulated by the sleeve 38 passes into the mixing chamber 6 and flows upwardly from the mixing chamber into the longitudinal conduit 17. The cross bar 16 aids in distributing the gas evenly along the channel iron 17. From the channel, the gaseous mixture flows laterally in the closure 11. At either side of the channel iron 17 and included in the closure are a plurality of burner bars 44, alternated with spacer strips 46. Angles 47 are secured to the sides of the burner bars and are bolted with an interposed gasket to the base plate 12. The entire assembly is held together by thru bolts 48. The spacer strips are regular rectangles in cross section while the burner bars are similar to the spacer strips in cross section but with the addition at intervals of enlargements 49 extending laterally and depending below the lower edge of the bar. The enlargements 49 form channels 50 transversely of the closure to aid in distributing the gas received from the longitudinal conduit 17 evenly over the entire series of fuel release apertures. This manner of constructing the fuel release apertures is particularly advisable inasmuch as expansion and contraction of the metal is substantially even over the entire series of apertures and does not tend to distort and reduce the size of some apertures and increase that of others. This effect is enhanced by the location of the bolts 48 in such a manner that the heat causes them to expand and contract in unison with the burner bars and spacer strips, thereby maintaining a constant relationship of the parts.

The initial heat for vaporizing the liquid fuel when the burner is started from cold is provided by a pan 52 having a filling of capillary material 53 such as asbestos, and provided with guides 54 at each end thereof. The guides are adapted to slide between flanges 56 formed with the supports 19 and overlying the longitudinal channel iron 17 and the burner bars and spacer strips. One of the guides 54 is formed into a convenient handle 57 by which the pan 52 can be inserted below the vaporizing tube 21. The material 53 is saturated with a volatile fuel which is ignited. The pan is then placed underneath the vaporizing tube and the heat evolved by the fuel in the pan readily vaporizes the fuel within the tube 21. The vaporized fuel issuing from the spray tip 32 enters with the proper proportion of air into the mixing chamber and is evenly distributed to the various channels within

the burner and issues in a uniform manner from the fuel release apertures where it is ignited and combustion proceeds. After combustion at the fuel release apertures has 5 been initiated, the starting pan 52 can be withdrawn as the heat evolved by the burner is sufficient to vaporize fuel within the vaporizing tube 21.

I claim:

- 10 1. A liquid fuel burner comprising a mixing chamber having a longitudinal opening therein, and a closure overlying said opening and having a longitudinal conduit forming an extension of said mixing chamber, said closure including a plurality of juxtaposed burner bars forming fuel release apertures therebetween and providing transverse channels connecting said apertures to said longitudinal conduit.
- 15 2. A liquid fuel burner comprising a mixing chamber having an opening therein, and a closure overlying said opening and having a conduit forming an extension of said mixing chamber, said closure including a plurality of juxtaposed burner bars having 25 recurring enlargements to form therebetween

groups of fuel release apertures and transverse channels connecting each of said groups to said conduit.

3. A liquid fuel burner comprising a closure including a base plate having an elongated aperture therein, a channel iron secured to said plate and overlying said aperture, the sides of said channel iron being partly cut away, a plurality of burner bars 30 secured to the side of said channel iron, and separator strips between said burner bars.

4. A liquid fuel burner comprising a closure including a base plate having an elongated aperture therein, a channel iron secured to said plate and overlying said aperture, said channel iron having portions of its sides spaced from said plate, a plurality of vertically disposed burner bars secured to one side of said channel iron, projections 40 extending laterally and depending from said bars, and separator strips contacting said projections and forming fuel release apertures therewith.

In testimony whereof, I have hereunto set 45 my hand.

JESSE E. KRESKY.
